UNITED STATES PATENT OFFICE.

EMIL J. HUGO, OF PHILADELPHIA, PENNSYLVANIA, ASSIGNOR TO LARGMAN, OPPENHEIM & CO., OF PHILADELPHIA, PENNSYLVANIA, A COPARTNERSHIP COMPOSED OF HARRY LARGMAN, JOSEPH LARGMAN, MAX M. OPPENHEIM, AND EMIL J. HUGO.

CORD WINDER.

Application filed August 22, 1923. Serial No. 658,763.

To all whom it may concern:

Be it known that I, EMIL J. HUGO, a citizen of the United States, residing at Philadelphia, county of Philadelphia, and State of Pennsylvania, have invented a new and useful Improvement in Cord Winders, of which the following is a full, clear, and exact description, reference being had to the accompanying drawings, which form a part of this specification.

My invention relates to an improved device for winding a thread upon a center core for the production of fancy cords, and more particularly my invention relates to an improved support for the spool or bobbin upon which the supply of covering thread is held and from which it is fed for winding upon the center core.

Heretofore the covering thread supply has been wound on a spool or bobbin and the spool supported to freely rotate on a spindle. The thread is led through guides to the center core which passes through the center of the spindle, the thread being drawn from the spool and spool being braked or tensioned by a cord frictionally engaging a groove in the spool and carrying a weight. Such devices have proved inefficient primarily because of the inefficiency of the tension device, which requires constant change of adjustment, as the diameter of the body of thread on the spool decreases in size, in order to approximate a constant equal tension. Further, due to inequalities in the tension on the wrapping thread and a certain amount of give and take in the core thread, it is extremely difficult to avoid the production of cord having a wavy effect or in other words cord in which the covering thread is wound unevenly on the core thread.

Now it is the object of my invention to provide a device of the character indicated, in which the covering thread will be under a constant equal tension irrespective of the diameter of the body of thread on the spool and in which there will be no tendency for the wrapping thread to be wound unevenly on the core thread.

Having now indicated in a general way the nature, purpose, and advantage of my invention, I will proceed to describe in detail a preferred embodiment thereof, with refer-

ence to the accompanying drawings, in which—

Fig. 1 is a plan view of a device embodying my invention.

Fig. 2 is a longitudinal view of the device shown in Fig. 1.

a represents any suitable support for a fixed spindle *b* upon the outer end of which is detachably secured a conical head *c*. The spindle is hollow and the thread is provided with a central bore in order to permit the passage of the center core thread *d*.

A sleeve *e*, upon one end of which is secured a pulley *f* adapted to be driven, is slipped over spindle *b* and is adapted to receive a spool *g* which carries a supply of covering thread *h*, the outer end of which is retained by the neck of head *c*.

A friction member *i*, loosely mounted on the sleeve and faced with felt *j* or other suitable friction is adapted to be yieldingly pressed against the inner end of the spool and to be driven by pulley *f* by means of a spring *k* secured to and positioned between the friction member and a head *l* carried by the pulley. Thus, the spool is positioned on the sleeve *e* between the neck of head *c* and friction member *i*.

The bearing of the friction member *i* against the end of the spool may be adjusted by varying the degree of compression of the spring *k* by moving the pulley through the medium of adjusting member *m* secured to support *a* by means of a wing nut *n*.

A flyer *o*, one arm of which is provided with a pulley *p* over which the thread *h* passes, is secured to the head *l* carried by the pulley and serves to lead the thread from the spool.

The operation of the device will, it is believed, be readily understood. A full spool of covering thread is slipped on the sleeve *e* after removal of head *c* from spindle *b*. The spool is positioned by the replacement of head *c* and the tension of spring *k* adjusted by manipulation of adjusting member *m*, which is secured by wing nut *n*. The end of the covering thread *h* is led over the pulley *p* of the flyer *o* and secured to the core thread *d* which is led through the spindle and head and attached to a suitably driven spool upon which it is wound as it is covered.

The belt f' is connected with power to rotate the pulley f which, through head l , spring k , friction member i and washer j , positively rotates the spool at the speed of 5 the pulley. The thread is unwound from the spool in the usual manner, which involves the rotation of the spool at a speed slightly greater than the speed that is imparted to it by the frictional drive. Thus, 10 the strain on the thread is minimized.

The covering thread constantly on tension as described is directed to the core thread over the end of head e and is wrapped around the core thread at the time when it 15 emerges from the head. Thus the head serves as a guide for the wrapping thread during the actual wrapping operation and the presence of any gap between the core thread and the guide for the core thread and 20 wrapping thread as it is wrapped is eliminated thus avoiding irregular wrapping.

It will be appreciated that the particular embodiment of the invention described is susceptible of various modifications and 25 changes without departure from my invention.

Having now fully described my invention, what I claim and desire to protect by Letters Patent is:

30 1. In a cord winder, in combination, a loosely mounted spool, a driven member, a friction member adapted to engage the spool, and means affording a yielding connection between said driven member and said friction member.

35 2. In a cord winder, in combination, a loosely mounted spool, a driven pulley, a flier positively driven by the pulley, a friction disc in engagement with an end of the 40 spool, and a spring secured to said disc and pulley adapted to act to hold said disc in engagement with said spool and afford a driving connection between said pulley and said disc.

45 3. In a cord winder, in combination, a loosely mounted spool, a driven pulley, a friction disc in engagement with an end of the spool, a compression spring secured to said disc and pulley and positioned there- 50 between and adapted to act to maintain said disc in engagement with said spool and afford a driving connection between said pulley and said disc, and means whereby the tension of said spring may be varied to 55 vary the degree of frictional engagement between said disc and said spool.

60 4. In a cord winder, in combination, a fixed spindle, a sleeve rotatably mounted thereon, a driven pulley secured to said sleeve, a spool loosely mounted on said sleeve, a friction disc loosely mounted on said sleeve and adapted to engage an end of the 65 spool, a spring secured to said friction disc and to said pulley and adapted to act to

force said friction disc against the end of 65 said pulley and afford a driving connection between said pulley and said friction disc.

5. In a cord winder, in combination, a spindle hollow for the passage of a core thread, a frictionally driven spool loosely 70 mounted thereon, a positively driven flier adapted to unwind a covering thread from said spool and wrap it about the core thread, and a head centrally bored for the passage of the core thread secured to the end of said 75 spindle and adapted to support and guide said core thread and covering thread as the latter is wrapped about the former.

6. In a cord winder, in combination, a loosely mounted spool, a driven pulley, a 80 flier positively driven by the pulley, a friction disc in engagement with an end of the spool, a spring secured to said disc and pulley adapted to act to hold said disc in engagement with said spool and afford a driving 85 connection between said pulley and said disc, and means for varying the tension of said spring.

7. In a cord winder, in combination, a fixed spindle, a sleeve rotatably mounted thereon, a driven pulley secured to said sleeve, a spool loosely mounted on said sleeve, a friction disc loosely mounted on said sleeve and adapted to engage an end of the spool, a spring secured to said friction disc and to 95 said pulley and adapted to act to force said friction disc against the end of said pulley and afford a driving connection between said pulley and said friction disc, and means for adjusting said driven pulley relative to said friction disc, whereby the tension of said spring may be varied.

8. In a cord winder, in combination, a fixed spindle hollow for the passage of a core thread, a sleeve rotatably mounted 105 thereon, a driven pulley secured to said sleeve, a spool, adapted to hold a covering thread, loosely mounted on said sleeve, a friction disc loosely mounted on said sleeve and adapted to engage an end of said spool, a spring secured to said friction disc and 110 said pulley and adapted to act to press said disc against the end of said space and act as a driving connection between said pulley and said disc, a rotating flier carried by 115 said pulley adapted to unwind thread from said spool and wrap it around a core thread, and a conical head centrally, bored for the passage of a core thread, secured on the end of said spindle and adapted to guide and 120 support the core thread and the covering thread as the latter is wrapped around the former.

In testimony of which invention, I have hereunto set my hand, at Philadelphia, Pa., 125 on this 16th day of August, 1923.

EMIL J. HUGO.
